PADDLE FOR CENTRIFUGAL THROWER

Walter W. Wolfe, 504, Route 1, Mound, Minn. 55364,
and Herbert A. Holten, 4728 Aldrich Ave., Minneapolis, Minn. 55340

Filed Mar. 6, 1968, Ser. No. 10,863

Term of patent 14 years

Int. Cl. D23—04

U.S. Cl. D23—165

FIGURE 1 is a side view of the paddle for a centrifugal thrower embodying our new design, with two paddles, the support spider, and outer housing shown in broken lines for illustrative purposes only.

FIGURE 2 is a first end perspective view thereof; FIGURE 3 is a second end perspective view thereof; FIGURE 4 is a first end elevational view thereof; FIGURE 5 is a side elevational view thereof; FIGURE 6 is a front elevational view thereof; and FIGURE 7 is a second end elevational view thereof.

We claim:

The ornamental design for a paddle for centrifugal thrower, as shown and described.
